UNITED STATES PATENT OFFICE

CHARLES V. LINDBLAD, OF BROOKLYN, NEW YORK, ASSIGNOR TO INTERNATIONAL CIGAR MACHINERY COMPANY, A CORPORATION OF NEW JERSEY

TENSION-EQUALIZING CHIANTI BELT TIGHTENER

Application filed September 15, 1927. Serial No. 219,646.

This invention relates to a tension-equalizing chianti belt tightener for cigar bunch machines.

In order to produce a tapered cigar bunch, a bunch rolling chianti belt is made of arcuate form and is rolled on a conical pin or roller, so that the traveling speed of various parts of the belt varies and produces a tendency of the belt to wrinkle at some points and to be unduly stretched at others.

The main object of the present invention is the production of a device whereby this tendency is avoided and more uniform bunches are produced. With this and other objects not specifically mentioned in view, the invention consists in certain constructions and combinations which will be hereinafter fully described and then specifically set forth in the claims hereunto appended.

In attaining the main object of the invention, the belt supporting roller of the cam-actuated belt tightening arm is mounted on a tension-equalizing head swiveled to the free end of the tightening arm, so that the roller can swing to the proper angle at every position of the rolling arm.

In the accompanying drawings, in which like characters of reference indicate the same or like parts, Fig. 1 is a plan view of a taper-rolling mechanism provided with the tension-equalizing chianti belt tightener; Fig. 2 is a side elevation of the structure shown in Fig. 1; and Fig. 3 is an end view of the belt tightening arm, showing the belt roller and its swivel mount on the arm.

In carrying the invention into effect, there is provided a tension-equalizing chianti belt tightener comprising an arm, means for oscillating said arm to tighten the belt, a tension-equalizing head swiveled to the free end of the arm, and means carried by said head and engaging the belt to equalize its tension when tightened. These various parts may be varied in construction within the scope of the claims. The invention, therefore, is not to be restricted to the precise details of the structure shown and described.

Referring to the drawings: The chianti belt 4 is fastened to the ends of a curved

rolling table 5 by means of strips 6 and 7. The belt covers the rolling top of the table 5, passes under the filler chute 8, in which a loading plunger 9 slides, then extends over the conical roller 10 of the rolling arm 11, 55 and finally passes around the roller 12 carried by a swiveled head 13 on the belt tightening arm 14. The rolling table 5 is attached to a bracket 15 supported by the table 16 of the machine. 60

The rolling arm 11 is pivoted on a stud 17 held in a bracket 18 attached to the table 16. The arm 11 has a lug 19 carrying a ball joint 20 which is connected by a rod 21 to a cam-controlled lever imparting oscillating movement to the rolling arm. When the rolling arm is in the position shown in full lines in Figs. 1 and 2, a charge of tobacco is delivered in the depressed pocket of the belt from the chute 8 by the plunger 9. As the arm 11 is advanced to the dotted position at the end of the rolling table, the charge is rolled into a binder B placed on the belt, thereby forming a cigar bunch C. At the end of the rolling table, the bunch 70 C is held by a clamp 24 pivoted on a pin 25 supported by a bracket 26 attached to the under side of the table 5, pressing it against the edge of the table by the action of a spring 27 on the pin 25. The guard plate 75 28, attached to the bracket 26, catches the bunch if it is missed by the clamp 24.

The belt tightening arm 14, which carries a swivel pin 29, is fulcrumed on a shaft 30 and held in tension by a spring 31 attached to a post 32 in the bracket 15. Its movement is controlled by a lever 33, attached to it by a pin 34, and at its free end carrying a roller 35 engaging a cam 36 on the main shaft 37 of the machine. The lever 33 has 80 a spur 38 engaging the adjusting screw 39 so that it can be accurately set to any required angle in accordance with the belt tension desired. The swivel head 13 being free to move in a clockwise direction, the roller 12 will automatically set itself to the proper angle to keep the belt in uniform tension. The stop 40, attached to the arm 14, limits the movement of the swivel in the opposite direction. To the swivel head 13 85 90 95 100

is attached a guard wire 41 which guides the belt and prevents it from interfering with the swivel movement of the head 13.

What is claimed is:

- 5 1. The combination with bunch rolling means having an arcuate chianti belt, of means for producing tension on said belt as a tapered bunch is rolled therein including positively actuated means for equalizing the tension as the bunch is rolled along its natural curved path by said belt. 70
- 15 2. The combination with bunch rolling means having an arcuate chianti belt, of means for producing tension on said belt as a tapered bunch is rolled therein including positively actuated means for equalizing the tension as the bunch is rolled along its natural curved path by said belt, said equalizing means being carried by said tension producing means. 80
- 25 3. The combination with bunch rolling means having an arcuate chianti belt, of means for producing tension on said belt as a tapered bunch is rolled therein including positively actuated means for equalizing the tension as the bunch is rolled along its natural curved path by said belt, said tension producing means including an oscillating arm engaging a bight of said belt to 90 double the movement of the belt with respect to the movement of the arm. 95
- 35 4. The combination with bunch rolling means having an arcuate chianti belt, of means for producing tension on said belt as a tapered bunch is rolled therein including positively actuated means for equalizing the tension as the bunch is rolled along its natural curved path by said belt, said tension producing means including an oscillating arm, and said equalizing means being carried by said arm. 100
- 45 5. The combination with bunch rolling means having an arcuate chianti belt, of means for producing tension on said belt as a tapered bunch is rolled therein including positively actuated means for equalizing the tension as the bunch is rolled along its natural curved path by said belt, said tension producing means including an oscillating arm, and said equalizing means including a head swiveled to the free end of said arm and connected with said belt. 110
- 55 6. The combination with bunch rolling means having an arcuate chianti belt, of means for producing tension on said belt as a tapered bunch is rolled therein including positively actuated means for equalizing the tension as the bunch is rolled along its natural curved path by said belt, said tension producing means including an oscillating arm, and said equalizing means including a head swiveled to the free end of said arm and carrying a roller engaging a bight of said belt. 120
- 65 7. The combination with bunch rolling 130

means having an arcuate chianti belt, of means for producing tension on said belt as a tapered bunch is rolled therein including positively actuated means for equalizing the tension as the bunch is rolled along its natural curved path by said belt, said tension producing means including a cam-actuated lever for tightening the belt and a spring for slackening the belt to receive a charge. 75

In testimony whereof, I have signed my name to this specification.

CHARLES V. LINDBLAD.
